UNITED STATES PATENT OFFICE.

RENÉ EDMOND LAHAUSSOIS, OF PARIS, FRANCE.

CARBURETER.

1,221,749.

Specification of Letters Patent. Patented Apr. 3, 1917.

Application filed March 13, 1915. Serial No. 14,287.

To all whom it may concern:

Be it known that I, RENÉ EDMOND LAHAUSSOIS, engineer, a citizen of the French Republic, residing at Paris, France, have invented certain new and useful Improvements in Carbureters, of which the following is a specification.

This invention relates to carbureters, more particularly for explosion engines, in which are used mixtures of combustible liquids such as heavy oils, schist oils, lighting petroleums and industrial alcohols.

The chief object of the invention is to render carbureters able to produce vaporizing of a constant and uniform quality, whatever be the quality of the substance to be vaporized, supplied to them and delivered per unit of time, and more particularly when the said carbureters are of the type used on explosion engines with variable speed, to enable such engines to work in better conditions than hitherto.

The invention consists in providing a carbureter, for atomizing as well as heating, so that to each modification of the atomizing corresponds a modification of the heating, so that when atomizing takes place, the temperature to which the oil or the like is brought, remains constant under any circumstances.

The invention further consists in certain other arrangements which will be more explicitly referred to hereinafter, more particularly an arrangement according to which, when it is desired to vaporize industrially a mixture of liquid, it is atomized in the presence of a heating body which in its turn is raised to such a temperature that the said mixture is immediately brought to its "eutectic" point, that is to say, to the temperature (hitherto simply considered as a temperature at which takes place a phenomenon curious from the purely scientific point of view) at which any mixture of liquid is vaporized without any dissociation taking place, and without any fractional distillation taking place before the vaporization.

In the accompanying drawing,

Figure 1 shows the carbureter diagrammatically in elevation, partly in section and with parts broken off.

Fig. 2 shows certain of the elements of the said carbureter in vertical section on the line 2—2 of Fig. 1.

According to the invention a sprayer *a* is provided suitable for producing, by radial

atomizing, a circular spray of particles traveling outward, and also a device for sending the liquid into the said sprayer with sufficient pressure.

The heating means, above referred to, consists of a cylindrical part or annular ring *b* arranged concentrically with the sprayer *a*, as well as at the same level and surrounded by an electric resistance *c* connected to a source of current suitable for feeding it, for example, storage batteries *d* which may be combined with the motor.

Both the sprayer and the heating means are arranged in an air tight chamber *e* so that the working takes place with the entire exclusion of air, in such conditions, that despite the presence of the heating means, the vaporized and atomized liquid cannot become ignited.

To the chamber is connected a nozzle *f* of an inlet *f* so that the vapors escaping from the said nozzle, can mix with air in the desired proportion, in order to form a suitable explosive mixture.

As soon as the atomized liquid comes into contact with the heating means, it is raised to its "eutectic" point, and as soon as the motor has been started, a more perfect working of the motor is obtained than when it is fed in the usual manner.

The nozzle of the sprayer *a* may form a Venturi nozzle, which can be advantageously effected, in the case where it is desired to distribute the liquid in a circular spray, by using a tubular part *a*¹ with a widened portion comprising a circular bevel 1, and also a rod *a*² which has a sliding fit in the said tube, as indicated at 2. The tube is also provided with a helical groove 3 and terminates at its outer end in a thickened portion *a*² also having a circular bevel 4. The two bevels are arranged to oppose each other and are preferably held at the proper distance apart by the liquid to be atomized, provided it is under sufficient pressure, and ultimately form the discharging nozzle of the sprayer.

The device for feeding the sprayer *a* is so arranged that its output is a function of the speed at which the motor is running. This arrangement is obtained by a suction and forcing pump *g* driven from the said motor, drawing from a constant level tank *h* and discharging into the said sprayer, the area of the discharging nozzle of which varies in cross-section in accordance with pressure

under which the liquid is placed by the speed of the motor.

A tube *i* with a pressure gage is provided, acting partially as the air reservoir of a pump.

5 A by-pass *g*¹ is provided on the pump *g* so that if the latter delivers too much, the liquid supplied can return directly to the tank from which it is taken.

10 A pipe *j* connects the bottom portion of the chamber *e* to the constant level tank *h* so that if the output of the sprayer *a* is excessive, the excess of liquid thus supplied, returns to the said tank which is preferably provided with a cooling arrangement, for 15 instance with ribs *k*¹.

15 A rod *k* exposed to the action of a spring *k*¹ acts on the widened portion *a*² of the central rod of the sprayer *a* and controls the 20 cross-sectional area of the nozzle in the reverse direction to the action exercised by the charge of liquid to be atomized.

25 The throttle *f*² of the said inlet *f* is connected to the atomizing means so that the output of the said means is determined by the position given to the said throttle (or conversely); this arrangement being obtained, by combining with the controlling rod *k*, a finger *l* adapted to press on the 30 same and mounted on a shaft *u* carried in a suitable bracket *v* and to which shaft is connected a connecting rod *m*, having suitable levers to the said throttle. A torsion spring *n* is provided for the shaft *u*, as shown in 35 Fig. 2.

The tube *i* is rendered suitable for storing, at each closure of the said throttle, a reserve of fuel calculated to facilitate the next starting or acceleration.

40 The source of electricity for feeding the resistance *c*, may not only be storage batteries *d*, but also an electro-magnetic machine *o* suitable for recharging the said batteries and connected to the motor so that its 45 speed is a function of the speed of the engine. The said machine can also be utilized as an automatic starting device suitable for starting the said motor, and its dimensions should be such that whatever be 50 the speed of the said motor, and therefore of the pump *g*, the resistance *c* always remains at the same temperature, in order to raise the atomized liquid impinging against it immediately to its "eutectic" point. The 55 machine should also be proportioned so the said resistance acts as an automatic regulator of current for recharging the batteries. For this reason, the machine *o* has two excitation series *o*¹ and *o*²—the first in 60 order to act as a self starter, and the second in order to act in its normal part. The free end of the said excitation series *o*¹ and the non-corresponding brush are connected respectively to the first and to the second of 65 the terminals of the batteries *d*, a switch *p*¹

being at the same time inserted into the circuit thus formed. From the same circuit is branched off a pair of conductors which are connected in a suitable manner to the resistance *c*. The free end of the said excitation series *o*² and the non-corresponding brush are connected respectively to the first of the terminals of the batteries *d* and to one of the ends of the resistance *c*. The second of the latter ends is connected to a 70 contact *q*, in front of which are mounted two other contacts *r* and *s* which are connected respectively to the second of the terminals of the batteries *d* and to a conductor branched on the conductor connecting the 75 said first terminal of the batteries *d* to the free end of the excitation series *o*². In the length of the latter conductor is inserted a switch *p*² which if desired could be connected to the said switch *p*¹ so that one 80 switch is opened when the other is closed and conversely. On the said contact *q* is mounted a kind of contact breaking switch *t* so that the latter connects the contacts *q* and *r* when the machine *o* rotates at the speeds 85 suitable for connecting it to the batteries *d*, and connects on the contrary the contacts *q* and *s* when the condition just formulated is not complied with.

The invention is not limited to the construction more particularly specified, but comprises on the contrary those modifications, in which it is applied to the feeding of explosion motors of all kinds and also to burners for steam generators; in which 90 case the invention would be the same as that described, with the difference that an inlet pipe would no longer be used and a separate engine connected to the distributing pump *g* and having automatic regulation, by completing the installation by combining a thermostat or pressure regulator with the same. 105

What I claim as my invention and desire to secure by Letters Patent is:—

1. A fuel vaporizing apparatus comprising, a heating surface, a fuel atomizer to direct the atomized fuel upon said heating surface, means controlling the supply of fuel to the atomizer, and automatically operated means for supplying a heating medium 115 to said surface in amounts proportionate to the supply of fuel to the atomizer.

2. A fuel vaporizing apparatus comprising, a heating surface, a fuel atomizer to direct the atomized fuel upon said heating 120 surface, means for placing the fuel under pressure and for controlling the amount supplied to the atomizer, and means coöperating with said first means for supplying a heating medium to said surface in amounts proportionate to the amount of fuel atomized.

3. A fuel vaporizing apparatus, comprising a heating surface, a fuel atomizer to direct the atomized fuel upon said surface, a 125 pump for supplying the fuel to the atomizer 130

- under pressure, an electrical means coöperating with said pump for supplying a heating medium to said surface in amounts proportionate to the amount of fuel atomized.
- 5 4. A fuel vaporizer comprising, a vaporizing chamber, an atomizer in the chamber for atomizing the fuel in a circular spray, means for controlling the supply of fuel to the atomizer, a substantially annular heating surface in the chamber encircling said atomizer and in the plane of said spray, and electrical means for heating said surface proportionately with the amount of fuel atomized.
- 10 5. A fuel vaporizer comprising, a vaporizing chamber, an atomizer in said chamber including a tubular member having one end chamfered and to which the fuel is supplied, a rod slidably disposed within said tube and having an enlarged end formed with a chamfered portion, the chamfered portions of said rod and tube coöperating to form a Venturi nozzle, and a heated surface disposed in said chamber and arranged in the plane of the
- 25 spray atomized by said nozzle.
6. A fuel vaporizer comprising a vaporizing chamber, an atomizer in said chamber including a tubular member having one end chamfered and to which the fuel is supplied, a rod slidably mounted in said tube and having an enlarged end formed with a chamfered portion, the chamfered portions of said rod and tube coöperating to form a circular Venturi nozzle, an annular heating
- 30 surface disposed in said chamber and surrounding said nozzle in the plane of the
- 35
- spray atomized thereby, and means for supplying fuel to said atomizer and the heating medium to said heating surface in proportionate amounts.
7. In a fuel vaporizer, a vaporizing chamber, an atomizer in said chamber, a fuel supply, a connection between said fuel supply and said atomizer, a pump interposed in said connection for forcing said fuel through said atomizer under pressure, a reservoir having connection with said connection for containing fuel under pressure to be used in priming, and a heating element in said vaporizing chamber upon which the atomized fuel is directed.
8. In a fuel vaporizer, a vaporizing chamber, an atomizer in said chamber comprising a tubular member having a cap for one end thereof in slidable engagement therewith, the contiguous portions of said cap and tube being chamfered and coöperating to form the atomizing nozzle, means for supplying fuel to said atomizer under pressure, said cap being relative to said tubular member under pressure of said fuel for varying the cross-sectional area of the nozzle, and operable means for controlling the movement of said cap caused by the pressure of the fuel.
